(57) **CLAIM**

The ornamental design for an aircraft sideledge, as shown and described.

DESCRIPTION

FIG. 1 is a front view showing our new design of an aircraft sideledge;

FIG. 2 is a perspective view of the aircraft sideledge of FIG. 1;

FIG. 3 is a first side view of the aircraft sideledge of FIG. 1; FIG. 4 is a view of a second side opposite the first side of the aircraft sideledge of FIG. 1;

FIG. 5 is a top view of the aircraft sideledge of FIG. 1; FIG. 6 is a close-up perspective view of a first portion of the aircraft sideledge of FIG. 1 as indicated in FIG. 2; and, FIG. 7 is a close-up perspective view of a second portion of the aircraft sideledge of FIG. 1 as indicated in FIG. 2.

In FIGS. 1-7, the dash-dash broken lines illustrate portions of the aircraft sideledge that form no part of the claimed design. The dot-dash broken lines illustrate the periphery of the enlarged views of the aircraft sideledge and form no part of the claimed design.
